COMBINATION PUMP AND MEDICINE AND WATER PROPORTIONER FOR POULTRY
OR THE LIKE

Nat Cordis, Crown Farm, Silver Lake, Wis.

Filed Apr. 18, 1960, Ser. No. 60,231

Term of patent 14 years

(Cl. D65—1)

The dominant features of the design are shown in full lines.

I claim:

The ornamental design for a combination pump and medicine and water proportioner for poultry or the like, as shown and described.
